FLOODLIGHT FOR HOSPITAL OPERATING
ROOMS, THEATRICAL STAGES AND THE
LIKE

Robert Rex Rudolph, 9610 22nd Ave. SW.,
Seattle 6, Wash.

Filed Apr. 15, 1963, Ser. No. 74,426

Term of patent 3½ years

(Cl. D48—20)

FIG 1

FIG 2

FIG 3

FIGURE 1 is a side elevational view of a floodlight for hospital operating rooms, theatrical stages and the like, showing my new design;

FIGURE 2 is a front elevational view thereof as shown in FIGURE 1;

FIGURE 3 is a top plan view thereof as shown in FIGURE 1.

The undisclosed side and end are the same in appearance as the side and end shown.

I claim:

The ornamental design for a floodlight for hospital operating rooms, theatrical stages and the like, as shown and described.
